UNITED STATES PATENT OFFICE.

ABRAHAM RITTER, OF NEW YORK, N. Y.

DESIGN FOR A BELT.

SPECIFICATION forming part of Design No. 33,535, dated November 6, 1900.

Application filed September 18, 1900. Serial No. 30,441. Term of patent 3½ years.

To all whom it may concern:

Be it known that I, ABRAHAM RITTER, a citizen of the United States, residing in the borough of Manhattan, in the city and State of New York, (whose post-office address is No. 2 East Ninety-seventh street, in said borough,) have invented and produced a new and original Design for Belts, of which the following is a specification, reference being had to the accompanying drawings, forming part thereof, in which—

Figure 1 is a perspective view of my belt with the ends buckled together. Fig. 2 is a plan view of the belt in its stretched-out condition.

The leading or material feature of my design consists of a band or belt having a central contracted portion 1 widening out into widely-separated broadened portions 2 and 3, forming downwardly-projecting points 4 5, which taper gradually into the widely-sepa-

rated contracted tongue-and-buckle ends 6 7, so that when the said tongue-and-buckle ends are brought together, as shown in Fig. 1, the upper edge of the belt will be approximately horizontal, and the points 4 5 will be disposed approximately opposite to each other and will flare outwardly and downwardly from the upper edge of the belt.

Having thus described my invention, what I claim as new, and desire to secure by Letters Patent, is—

The design for a belt as herein shown and described.

In testimony whereof I have signed my name to this specification in the presence of two subscribing witnesses.

ABRAHAM RITTER.
